UNITED STATES PATENT OFFICE.

VANCE P. JACKSON, OF TRENTON, NEW JERSEY, ASSIGNOR TO GLOBE RUBBER TIRE MFG. CO., INC., OF TRENTON, NEW JERSEY, A CORPORATION OF DELAWARE.

DESIGN FOR A RUBBER TIRE.

49,213.

Specification for Design.

Patented June 20, 1916.

Application filed April 10, 1916. Serial No. 90,261. Term of patent 14 years.

To all whom it may concern:

Be it known that I, VANCE P. JACKSON, a citizen of the United States, residing at Trenton, in the county of Mercer and State of New Jersey, have invented a new, original, and ornamental Design for Rubber Tires, as shown in the accompanying drawing and described in the following specification.

Referring to the drawing, Figure 1 shows

a plan view of a portion of the tire showing this design, and Fig. 2 is a cross sectional view therethrough.

I claim:—

The ornamental design for a rubber tire as shown.

VANCE P. JACKSON.

Witnesses:

L. H. ARCHER,

WILLIAM T. HOFFMAN.
